ALTERNATING VOLTAGE REGULATOR

Oliver H. Winn, Baldwinsville, N. Y., assignor to
 General Electric Company, a corporation of
 New York

Application June 13, 1947, Serial No. 754,383

8 Claims. (Cl. 323—89)

1

My invention relates to alternating voltage regulators and particularly to an electronic voltage regulator for minimizing load voltage variations due either to input voltage variations or load current variations.

It is an object of my invention to provide an improved alternating voltage regulator which provides a regulated output voltage, the root-mean-square value of which is constant within very small limits. This is a particularly desirable type of regulating action for an electric heating load which is to be maintained at constant temperature, for example, since it is well known that the heating effect is dependent upon the root-mean-square (hereinafter abbreviated to R. M. S.) value of the applied voltage rather than the peak or average values of applied voltage.

It is a more specific object of my invention to provide an improved electronic alternating voltage regulator having no moving parts and which will maintain a substantially constant R. M. S. voltage output independent of changes in the wave form of the applied voltage.

Still another object of my invention is to provide an improved all-electronic alternating voltage regulator which is simple and energized entirely from the source of current to be regulated.

Still a further object of my invention is to provide an improved alternating voltage regulator which is particularly suitable for energizing an electric heating load and which tends to maintain constant absolute load temperature independent of ambient temperature changes. Although it is not limited thereto, my invention has particular utility in a regulated voltage supply for the tube filaments of a radio transmitter, receiver, or similar electronic apparatus.

The features of my invention which I believe to be novel are set forth with particularity in the appended claims. My invention itself, however, together with further objects and advantages thereof, may best be understood by reference to the following description taken in connection with the accompanying drawings in which Fig. 1 is a schematic circuit diagram of an alternating voltage regulator embodying the invention; and Figs. 2 and 3 are curves illustrating the electrical performance of a particular voltage regulator embodying the invention.

The regulator of Fig. 1 has a pair of input terminals 10, adapted to be connected to a suitable source of alternating current power, and a pair of output terminals 11 adapted to be connected to an alternating current load. The lower terminals 10—11 may be grounded, as illustrated. The load

2

voltage regulation is accomplished by means of a saturable reactor 12, which may be of conventional design, connected in series between the upper pair of terminals 10—11. The reactor 12 is conventionally represented as comprising a pair of reversely-connected windings 12a and 12b and a direct current saturating winding 13. As is well known, the effective reactance between the terminals 14 and 15 of the reactor 12 is readily varied by varying the direct current supplied through the saturating winding 13.

In the illustrated embodiment of Fig. 1, it is desired to have the output voltage at terminals 11 substantially the same as the input voltage at terminals 10. Since the reactor 12 introduces a certain voltage drop between the input and output terminals, this is compensated by means of a step-up voltage transformation in certain of the windings of a transformer 16 connected to the load side 15 of the reactor 12. As illustrated, the transformer 16 includes a shunt primary winding section 16a connected from point 15 and through a tap 17 to ground, and a series secondary winding 16b connected between point 15 and the upper output terminal 11. The polarity of the voltage induced in the winding 16b is such as to oppose the voltage drop through the reactor 12. Transformer 16 also comprises an additional autotransformer section 16c and a further winding 16d, the functions of which will become apparent as the description proceeds. In some cases it may be desirable to omit the series winding 16b and to connect the upper output terminal 11 to a proper voltage point on the autotransformer secondary winding 16c.

The regulating action is accomplished by varying the average value of direct current through the saturating winding 13 as a function of the R. M. S. value of voltage at the load side of the regulator. The circuits for accomplishing this in accordance with the invention comprise the electron discharge devices 20, 21 and 22 and their interconnecting circuits, including a resistance bridge 23, now to be more particularly described.

The resistance bridge 23 comprises a pair of diagonally opposite resistance arms R₁ and R₂ which have substantially constant resistances over the voltage control range. The other pair of diagonally opposite bridge arms R_{F1} and R_{F2} consist of non-linear resistances which vary substantially as a function of the R. M. S. value of applied voltage over the control range. This type of resistance characteristic may be provided by various materials and resistor constructions known to the art, but it is very conveniently pro-

vided in this case by utilizing the cathode heating filaments 24 and 25 of the discharge devices 21 and 22, respectively. These filaments then perform the dual function of heating the cathodes of these discharge devices and providing the desired resistance arms for the control bridge. The bridge balance may be adjusted by moving contact 18 on resistor R₁ to short-circuit a selectable portion of R₁. An alternating voltage E_i, proportional to the output load voltage, is impressed across one diagonal 26-27 of the bridge 23 from the transformer winding 16d, and an alternating error voltage E_o, utilized to effect the regulating action, is derived from the other diagonal 28-29 of the bridge. Terminal 29 is grounded, as shown, and the alternating error voltages appearing between point 28 and ground are impressed upon the grid circuit of the two-stage voltage amplifier comprising the discharge device 21 and its associated circuits.

Discharge device 21 is represented as a dual triode having a first stage comprising the left-hand triode section 21a and a second stage comprising the right-hand triode section 21b. These are capacitance-resistance coupled in conventional manner and the voltage output of the right-hand section 21b is further coupled to the control grid of the discharge device 22, represented as a pentode amplifier. Suitable anode operating potentials for device 21 and grid bias potentials for the devices 21 and 22 are supplied from the discharge device 20 and its associated circuits. The device 20 is represented as a dual diode having a left-hand diode section 20a connected in a conventional half-wave rectifier circuit across the input terminals 10 and having a right-hand diode section 20b also connected in another conventional half-wave rectifier circuit across the input terminals 10. As will be evident in the drawing, the rectifier polarities are such that negative voltages suitable for biasing the grids of devices 21 and 22 are developed at point 30 and positive voltages suitable for energizing the anodes of device 21 are developed at point 31. The common heating filament for the discharge device 20 may be energized from a suitable tapped portion of the transformer winding 16d, as shown.

An alternating anode operating potential is supplied to the discharge device 22 from the autotransformer 16a-16c through the saturating winding 13. The device 22 is biased to operate as a grid-controlled, high-vacuum rectifier and the average value of direct current flowing in its anode circuit through the saturating winding 13 determines the alternating voltage drop across the saturable reactor 12. The anode current is smoothed by means of the relatively large capacitor 33 in shunt to the saturating winding 13.

In analyzing the operation of the system of Fig. 1, assume for the moment that the instantaneous alternating potentials across the several transformer windings, and the instantaneous values of the input and output bridge voltage E_i and E_o have the polarities with respect to ground indicated by the plus and minus signs and the voltage arrows.

Considering first the operation of the bridge network R₁, R₂, R_{F1}, R_{F2} alone, the filament resistances R_{F1} and R_{F2} vary with voltage according to the same function (i. e., they have the same percent change in resistance for a given voltage change). Therefore:

$$R_{F1} = kR_{F2} \quad (1)$$

where *k* is some constant. At normal bridge balance, the bridge is adjusted so that

$$R_1 = R_{F1} \text{ and } R_2 = R_{F2} \quad (2)$$

and under these conditions, if the filaments are of the same rating, one-half the input voltage E_i appears across each filament. For example, if the normal filament voltage is 6.3 volts, the transformer is designed to supply 12.6 volts at rated output voltage of the regulating system:

At balance, then

$$\frac{R_1}{R_2} = \frac{R_{F1}}{R_{F2}} \quad (3)$$

15 and

$$R_1 = kR_2 \text{ and } R_{F1} = kR_{F2} \quad (4)$$

The general bridge formula for output voltage E_o, using the indicated instantaneous polarities, is:

$$E_o = E_i \frac{R_2}{R_2 + R_{F2}} - E_i \frac{R_{F1}}{R_{F1} + R_1} \quad (5)$$

or

$$E_o = E_i \left[\frac{R_2}{R_2 + R_{F2}} - \frac{R_{F1}}{R_{F1} + R_1} \right] \quad (6)$$

Substituting from Eq. 2 and Eq. 4 in Eq. 6:

$$E_o = E_i \left[\frac{R_1 - R_{F1}}{R_1 + R_{F1}} \right] \quad (7)$$

and E_o at balance is zero.

Since filament resistance increases as a function of input voltage and temperature, if E_i now rises, R_{F1} becomes greater than R₁ and R_{F2} greater than R₂. From Eq. 6, it will be seen that E_o is negative, or out-of-phase with E_i. If E_i decreases, the converse is true and E_o becomes positive, or in-phase with E_i.

Since the change in filament resistance is a function only of filament temperature, which in turn is a function of the R. M. S. value of input voltage, it will be apparent that the bridge can respond only to a change in the R. M. S. value of E_i; and the relation of E_o to E_i is substantially linear over the effective regulating range, because of the high voltage gain of the regulating system which keeps the net change in E_i within very narrow limits.

The complete sequence of control operations will now be briefly traced, assuming for illustration that the regulator output voltage tends to rise and that the instantaneous alternating current potentials have the polarities indicated by the arrows and the plus and minus signs of Fig. 1.

1. As previously pointed out in the analysis of operation of bridge 23, when the voltage E_i (which is proportional to the regulator output voltage) rises, a negative or out-of-phase voltage E_o appears at point 28. This is applied to the grid of amplifier section 21a. Since the grid and anode voltages of each of the amplifier sections 21a and 21b are out-of-phase, the instantaneous voltage at the grid of 21b is represented by a plus sign and the voltage at the grid of pentode 22 by a minus sign. Since the polarities of the transformer windings are such that the anode voltage of tube 22 is "plus" at this instant, the grid-voltage is in phase opposition to the anode voltage and the result is a decrease in the average value of the rectified anode current flowing through saturating winding 13. The reactance of reactor 12 consequently increases, reducing the regulator output voltage to nearly the value before the change.

The effectiveness of an actual voltage regulator

of the type illustrated in Fig. 1 is shown by the test curves of Figs. 2 and 3. Fig. 2 shows the R. M. S. value of alternating output voltage plotted against the R. M. S. value of output current. It will be observed that the voltage change was only about 0.2 volt at approximately 117 volts for a load change from 0.8 amp. to 2.70 amp. Fig. 3 shows the R. M. S. value of alternating output voltage plotted against changes in the R. M. S. value of the alternating input voltage. It will be seen from this curve that the output voltage change only about 0.1 volt from a value of approximately 117 volts for an input voltage variation over the range of about 105 to 133 volts.

Another useful characteristic of the regulator of my invention is the fact that it tends to maintain constant filament temperatures for the filaments 24 and 25 regardless of changes in ambient temperature. Therefore, the regulator will cause the output voltage to vary slightly with the ambient temperature. This is valuable when the alternating current load consists of the tube filaments of a transmitter, receiver, or similar electronic equipment, because the regulator will tend to maintain a constant filament temperature at these tubes as well (assuming that they are subjected to the same ambient temperature as the filaments 24 and 25). It would be possible to select materials of the proper temperature coefficients for the bridge arms R_1 and R_2 so as to compensate for this effect and to provide constant output voltage independent of changes in ambient temperature. However, the voltage variation with changes in ambient temperature is very small and this would generally be an unnecessary refinement even where substantially constant output voltage is desired.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. A system for regulating the voltage supplied from an alternating current source to an alternating current load comprising a variable impedance element in series between said source and load, a non-linear bridge network having an output impedance which varies as a function of the root-mean-square value of voltage applied to its input, means for energizing said input in response to the voltage at the load side of said impedance, said network developing an alternating error voltage at said output having a magnitude dependent upon the extent of said variations from a predetermined value and being either in-phase or out-of-phase with the load voltage dependent upon the direction of said variation, and means responsive to said alternating error voltage for continuously varying the impedance of said element in a sense to reduce said variations.

2. A system for regulating the voltage supplied from an alternating current source to an alternating current load comprising a variable impedance in series between said source and load, means for deriving an alternating control potential proportional to the voltage supplied to said load, a bridge network having one diagonal energized from said potential, one pair of diagonally-70 opposite bridge arms consisting of substantially

linear resistances and the other pair consisting of nonlinear resistances whose resistance varies substantially as a function of the root-mean-square value of said potential, and means responsive to the alternating voltage across the other diagonal of said bridge for continuously varying said impedance in a sense to reduce said variations.

3. An alternating voltage regulator comprising a saturable series reactor adapted to be connected between an alternating voltage source and load and having a direct-current saturating winding, a resistance bridge having one diagonal energized in proportion to the alternating load voltage, one pair of diagonally-opposite bridge arms having substantially constant resistances over a predetermined voltage control range and the other pair having non-linear resistances varying as a function of the root-mean-square value of voltage over said range, means for amplifying alternating potentials appearing across the other diagonal of said bridge, means responsive to said amplified potentials for developing a direct current, and means for continuously supplying said current to said saturating winding in polarity to reduce load voltage variations.

4. An alternating voltage regulator comprising a variable impedance adapted to be connected in series between an alternating current source and load, means comprising a non-linear resistance bridge having one diagonal energized in response to the voltage across said load for developing an alternating control voltage across the other diagonal which varies as a function of variations in the root-mean-square value of load voltage over a predetermined control range, said control voltage having zero magnitude for a predetermined desired load voltage and increasing in in-phase relation with said load voltage for variations in one direction and increasing in out-of-phase relation for variations in the opposite direction, and means for continuously varying the value of said impedance in response to said control voltage in a sense to reduce said variations.

5. In an alternating voltage regulator having input and output terminals for connection between an alternating current source and load, a saturable reactor in series circuit between said terminals having a saturating winding, an electronic rectifying device having a control grid and an anode, an anode circuit for said device including said winding and energized in accordance with the alternating output voltage at said output terminals, means responsive to said voltage for developing an alternating control potential having relative phase and magnitude continuously determined by output voltage variations above and below a predetermined value, and means for impressing said alternating potential on said control grid, thereby to control the average direct current in said anode circuit and saturating winding.

6. In an alternating voltage regulator having input and output terminals for connection between an alternating current source and load, a saturable reactor in series circuit between said terminals having a saturating winding, an electronic rectifying device having a control grid and an anode, an anode circuit for said device including said winding and energized in accordance with the alternating output voltage at said output terminals, means responsive to variations in said output voltage for developing an alter-

7
nating error potential, said potential having either an in-phase or an out-of-phase relation to said voltage as said voltage varies away from a predetermined value and having a magnitude determined by the degree of said variation, and means for impressing said alternating potential on said grid in such phase relation as to cause compensatory load voltage variations due to change in anode current through said saturating winding.

7. An alternating voltage regulator comprising a saturable series reactor adapted to be connected between an alternating voltage source and load and having a direct-current saturating winding, a resistance bridge having one diagonal energized in proportion to the alternating load voltage, one pair of diagonally-opposite bridge arms having substantially constant resistances over a predetermined voltage control range and the other pair comprising a pair of thermionic tube filaments having resistances varying substantially as a function of the root-mean-square value of voltage over said range, means responsive to alternating potentials appearing across the other diagonal of said bridge for developing 15 a direct current which is a function of said potentials, and means for continuously supplying said current to said saturating winding in polarity to oppose load voltage variations.

8. An alternating voltage regulator comprising 30 a saturable series reactor adapted to be connected between an alternating voltage source and load and having a direct-current saturating

5
winding, a resistance bridge having one diagonal energized in proportion to the alternating load voltage, one pair of diagonally-opposite bridge arms having substantially constant resistances over a predetermined voltage control range and the other pair comprising a pair of thermionic tube filaments having resistances varying substantially as a function of the root-mean-square value of voltage over said range, means for amplifying alternating potentials appearing across said other diagonal, an electronic rectifying device having anode and control grid circuits, said anode circuit including said saturating winding and being energized in response to said load voltage, and means for impressing said amplified alternating potentials on said grid circuit in such sense that the variations in average anode current through said winding cause said load voltage variations to be reduced.
